METHOD OF TREATING SUGAR

Horace S. Isbell, Washington, D. C., assignor to
the Government of the United StatesNo Drawing. Application June 24, 1941,
Serial No. 399,533

10 Claims. (Cl. 127—63)

(Granted under the act of March 3, 1883, as
amended April 30, 1928; 370 O. G. 757)

1

The invention described herein may be manufactured and used by or for the Government for governmental purposes without the payment to me of any royalty thereon.

The present invention relates to a method of treating sugar.

It is an object of the present invention to provide an improved method for the bleaching of sugar, wherein the colored impurities are bleached, without appreciable modification or destruction of the sucrose.

Another object of the invention is to provide a method of treating sugar which effects a bleaching action and also prevents bacterial action. Other objects of the invention will appear more fully from the following specification.

Heretofore, various chemicals, such as chlorine, hypochlorites and peroxides have been separately used for bleaching sugar solutions, but these have not been wholly satisfactory because they attack and destroy at least part of the sucrose. Furthermore, when the bleaching agent reacts with the sucrose, it is not available for reaction with the impurities.

In accordance with the present invention, these undesirable results are overcome by a process wherein the sugar or sugar solution is subjected to a simple chemical treatment which bleaches the impurities without destroying or causing the deterioration of the sucrose. This treatment contemplates broadly the bleaching of the sugar by the use of a soluble chlorite of a non-toxic metal, such as sodium chlorite, calcium chlorite, or magnesium chlorite.

The invention also contemplates a process wherein the rate of bleaching may be regulated. This may be accomplished by adjusting the acidity of the sugar chlorite mixture or by the addition of an expediting agent. The acidity of the mixture may be controlled by the addition of acids, such as sulphuric or phosphoric acids; or by the addition of a base or buffering agent, such as calcium carbonate or sodium bicarbonate. If a slow rate of bleaching is desired, with particular emphasis on the prolonged germicidal action of the chlorite, the buffering or neutralizing agent is added to the sugar chlorite mixture, thereby controlling the acidity thereof and also preventing acid hydrolysis of the sucrose. If a more rapid rate of bleaching is desired, the acidity of the mixture is increased, or an expediting agent is added taken from the group comprising chlorine, bromine, iodine, and hypochlorites. The resulting quickening of the bleaching action

2

more than compensates for the slight sugar destruction due to the expediting agent.

The practice of the invention is illustrated by the following examples wherein ordinary laboratory equipment may be used.

Example 1

The raw sugar is dissolved in an equal weight of water and mixed with an aqueous chlorite solution in the proportion of 4 parts of sodium, calcium or magnesium chlorite per 1000 parts of sugar. The solution is allowed to stand four days at room temperature. During this period, the color of the sugar solution decreases from an original value of $-\log_{50}t = .047$ to a value of $-\log_{50}t = .00365$, or approximately 92%. In this and subsequent examples, the color is measured by the method described by Brewster in the 1936 "Journal Research National Bureau of Standards," volume 16, page 349.

If 1 part of sodium, calcium or magnesium chlorite per 1000 parts of sugar is used, the color reduction is from $-\log_{50}t = .047$ to .0055, or approximately 80%. The amount of chlorite added depends on the amount and character of the impurities to be bleached, and it also depends on the desired degree of bleaching.

The sugar solution containing the chlorite is now heated to approximately 80° C. and filtered. The filtered solution may be run through a column containing a decolorizing carbon, such as animal charcoal, for the purpose of further decolorization and clarification. Experience has shown that the purifying effect of the decolorizing carbon is greatly increased by the previous treatment of the sugar solution with the chlorite.

The sugar solution is finally concentrated in vacuo and brought to crystallization. The resulting white crystals may be separated on a centrifugal.

Example 2

The raw sugar is mixed with an equal weight of water and with .5 part calcium chlorite per 1000 parts of sugar, and the solution is made slightly acid by the addition of an acid, say phosphoric acid. The solution is heated to approximately 70° C. and filtered. The filtered solution is concentrated in vacuo and brought to crystallization. The resulting colorless crystals are separated in known manner.

The reason for making the solution acid is that the bleaching action is more rapid in acid than in neutral or alkaline solutions. However, since sucrose is hydrolyzed in strongly acid solution, it is necessary to regulate the acidity during the

bleaching operation. The higher practical limit for acidity is approximately pH 4.

The use of phosphoric acid in conjunction with the calcium chlorite is particularly advantageous. Not only is the bleaching effect accelerated by the acid, but the precipitation of the resulting calcium phosphate causes the removal of colloidal matter from the sugar solution.

Example 3

A raw sugar solution of 60 Brix is heated to 75° C. and mixed with milk of lime to give an alkaline reaction with phenolphthalein. Calcium chlorite is added in the proportion of .3 part of chlorite to each 1000 parts of sugar. After mixing, the alkalinity is neutralized with monocalcium phosphate in sufficient quantity to give a precipitate that separates sharply from solution. The warm solution is then filtered. The filtrate is treated with decolorizing carbon, filtered again and concentrated in vacuo. The resulting white crystals are separated in conventional manner.

Example 4

The raw sugar is dissolved in an equal weight of water and is mixed with a 10% aqueous sodium chlorite solution in the proportion of 1 part sodium chlorite per 1000 parts of sugar. The acidity is adjusted to, say, pH 5 by the addition of phosphoric acid. A 10% aqueous sodium hypochlorite solution is added, as an expediting agent, in the proportion of 2 parts sodium hypochlorite per 1000 parts of sugar. The bleaching action occurs rapidly and appears to be substantially complete in thirty minutes. The solution may be filtered over decolorizing carbon and concentrated to give colorless crystalline sugar.

Should the acidity be adjusted to pH 7, instead of pH 5, the bleaching action is less rapid but still satisfactory, and a colorless crystalline sugar is obtained. At approximately pH 8, bleaching still occurs, but only to a very limited extent.

Similar runs using calcium chlorite and sodium or calcium hypochlorite, instead of sodium chlorite and sodium hypochlorite, give equally satisfactory results. The relative proportions of hypochlorite and chlorite, whether calcium or sodium, may be varied over a considerable range. Satisfactory results are obtained with from 1 to 4 parts of hypochlorite per part of chlorite.

Example 5

13 grams of blackstrap molasses is dissolved in water to make 100 ml and treated, at room temperature, with 1 gram of sodium chlorite. In the course of eighteen hours, the color decreases from $-\log_{10} E = .253$ to $-\log_{10} E = .00807$, or approximately 97%. Upon treating the solution with 1 gram of carbon and filtering, the color further decreases to $-\log_{10} E = .00643$.

Should it be desirable to expedite further the bleaching operation, chlorine, bromine, iodine or hypochlorite may be added in the proportion of from 1 to 2 parts per part of sodium chlorite.

Example 6

Raw sugar is mixed with a sugar syrup containing about 5 grams of calcium, sodium or magnesium chlorite per liter, to form a magma. Chlorine gas is then introduced into the magma, as an expediting agent, to bring the acidity to, say, pH 5. The magma, which contains the bleached crystals, is now transferred to a centrifugal and the crystals separated. The syrup

remaining after the removal of the bleached crystals contains the unused calcium chlorite. This syrup may be used again for preparing subsequent magmas. When the impurities in the syrup become sufficiently high, the sugar is reclaimed therefrom in known manner.

While this example refers to the use of a chlorite in conjunction with chlorine, the process may also be used with a chlorite alone, or with a chlorite in conjunction with expediting compounds other than chlorine, such as iodine, bromine and hypochlorites.

Example 7

15 A 1 kg. sample of raw sugar is treated with 10 ml of a 10% solution of calcium, sodium or magnesium chlorite by spraying the solution on the sugar. On standing, the color of the treated raw sugar decreases perceptibly in the course of one day, and continues to decrease with time.

20 Should it be desirable to control the acidity of the sugar mixture containing the chlorite, calcium carbonate or other buffering agent may be added. The calcium carbonate thus prevents hydrolysis of the sugar, and the chlorite prevents bacterial action. This is particularly important when the sugar is held in storage.

25 A particularly important commercial application of the process embodying the invention is in the preparation of refined sugar. The chlorite, with or without the expediting agent (chlorine, bromine, iodine, acid, hypochlorites) may be added to the massecuite, which is prepared from the cane juice, and permitted to react in the conventional crystallizer; or it may be sprayed

30 upon the raw sugar in the "centrifugal," in which event the small quantity of chlorite remaining with the resulting raw sugar prevents bacterial action during storage, while continuing with a slow bleaching action; or it may be introduced into the "mingling machine" with the raw sugar and syrup during the washing process; or it may be introduced into the "melt" either before or after filtration.

35 The invention may be variously modified and embodied within the scope of the subjoined claims.

I claim:

1. The method which comprises subjecting crystalline sugar to the action of a solution containing a chlorite in an amount from approximately .02% to .5% of the weight of the dry sucrose, with the hydrogen ion concentration lying between pH 4 and pH 8.

40 2. The method which consists in subjecting crystalline sugar to the action of a solution containing a chlorite to effect a bleaching action and a preservative action.

45 3. The method which comprises subjecting crystalline sugar to the action of a solution containing a chlorite in an amount from approximately .02% to .5% of the weight of the dry sucrose, in the presence of calcium carbonate in an amount sufficient to maintain the hydrogen ion concentration in the pH range of 4 to 8.

50 4. The method which consists in subjecting raw sugar, while in crystalline form, to the action of a solution containing a chlorite and a neutralizing buffering agent in quantity sufficient to maintain a substantially neutral reaction, to effect a bleaching action and a prolonged bactericidal effect.

55 5. The method which consists in subjecting a sugar massecuite to the action of a solution con-

taining a chlorite, and separating the treated crystals.

6. The method which consists in subjecting crystalline sucrose to the action of a solution containing a chlorite and a hypochlorite, and separating the treated crystals.

7. The method which comprises subjecting crystalline sugar to the action of a solution containing sodium chlorite to effect a bleaching of the colored impurities, while simultaneously preventing bacterial action.

8. The method which comprises subjecting crystalline sugar to the action of a solution containing calcium chlorite to effect a bleaching of the colored impurities, while simultaneously preventing bacterial action.

9. The method which comprises subjecting crystalline sugar to the action of a solution containing magnesium chlorite to effect a bleaching and preservative action.

10. The method of bleaching crystalline sugar, while simultaneously preventing bacterial action, which comprises subjecting the crystalline sugar to the action of a solution containing a chlorite of a non-toxic metal, with the hydrogen ion concentration lying between pH 4 and pH 8.
